UNITED STATES PATENT OFFICE.

JOHN W. FITZ GERALD, OF DETROIT, MICHIGAN.

REGULATOR FOR ELECTRIC-LIGHTING SYSTEMS ON MOTOR-VEHICLES.

1,373,806.

Specification of Letters Patent.

Patented Apr. 5, 1921.

Application filed March 23, 1918. Serial No. 224,151.

To all whom it may concern:

Be it known that I, JOHN W. FITZ GERALD, a citizen of the United States of America, residing at Detroit, in the county of Wayne 5 and State of Michigan, have invented certain new and useful Improvements in Regulators for Electric-Lighting Systems on Motor-Vehicles, of which the following is a specification, reference being had therein to 10 the accompanying drawings.

The invention relates to regulators for electric currents, being more particularly designed for use in connection with lighting systems for motor vehicles, such for instance 15 as systems adapted for installation on the "Ford" type of car. In this type the current for the lights is obtained directly from the magneto generator without the use of a storage battery, and it is usual to place 20 the lamps for the two headlights in series with each other. The resistance of the two lamps thus placed is such as to obtain the desired illumination when running at normal speed, but an increase in speed will produce 25 an objectionable intensity of light, while at low speed the illumination is insufficient.

To overcome these difficulties I have devised a system in which, instead of placing 30 the two lights in series, they are arranged in multiple or in independent circuits. This will lower the resistance sufficiently so that in starting and when the motor is running at low speed there will still be sufficient current 35 passing through the lamp circuit to produce proper illumination. To control the current at higher speeds I place in the circuit a resistance device, by means of which resistance is added as the voltage increases 40 so as to maintain nearly a constant current through each lamp. Provision is also made for preventing the cutting in of this resistance until a predetermined current is flowing through the lamp circuit, and 45 for then cutting in the resistance in progressively lessening increments corresponding to the curve of the voltage rise. Thus with my improved system the illumination is substantially constant without regard to the 50 speed.

In the drawings:

Figure 1 is a diagram showing my improved system;

Fig. 2 is a similar view illustrating a 55 modification.

A is the magneto generator and B and B' are the lamps for the two headlights which

are included in separate circuits C and C'. In each of these circuits is arranged in series with the lamp a regulator D, preferably of 60 the following construction.

E is a casing, within which is arranged a variable resistor F, the resistance of which is lowered by compression and is raised by expansion. As shown in Fig. 1, the resistor 65 is formed of a series of annular disks of carbonized cloth or other suitable material having a relatively high resistance and possessing a degree of resiliency which permits expansion on release of pressure. Through the 70 space within these disks extends a conductor G which has a relatively high coefficient of expansion and is so proportioned in resistance as to rise in temperature rapidly within a relatively small variation of current volume. Preferably I employ silver 75 wire on account of its high coefficient of expansion and high electrical conductivity. One end of the wire G is attached to a movable follower H at one end of the casing E 80 and bearing against the resistor. The other end of the conductor G passes out from the casing and is attached to a spring I. The follower H is also attached to a spring J tensioned to exert a pull in the opposite direction from that of the spring I, but to a lesser degree. The conductor G and resistor F are included in the lamp circuit, the current being conveyed to the conductor G through a contact member K slidably bearing 85 thereon, and from this conductor to the follower H and resistor F, the opposite end of which is connected to the conductor of the lamp circuit. L is a stop member secured to the conductor G and adapted on a predetermined 90 expansion of the latter to contact with the member K, which then co-operates 95 to arrest further movement.

With the construction as thus far described in operation, the tension of the 100 spring I acting through the wire G upon the follower H will compress the resistor F so as to lower the resistance thereof to the minimum. This will so lower the resistance of the lamp circuit that when the generator 105 is running at low speed and is at relatively low voltage, there will still be current enough passing through the circuit to produce good illumination. As soon as there is any current flowing through the circuit the 110 heat generated in the wire G will cause the expansion of the same, but the expansion of the spring I is sufficient to maintain the wire G taut and to exert substantially the

same pull thereon. This continues until the expansion is sufficient to bring the stop L into contact with the coöperating stop K, which arrests further movement in this direction. 5 With continued increase in the current volume the wire G is further expanded and as the spring I can no longer take up this expansion the spring J comes into action and draws the wire and the follower H in 10 the opposite direction. This, by releasing pressure upon the resistor F, will increase the resistance thereof, and as the current is compelled to traverse this resistor in passing through the lamp circuit the flow of current will be controlled. The same action 15 will continue throughout the entire range of variation of speed and voltage of the generator, and although there is a constant rise in current volume passing through the 20 lamp circuit the increase is nevertheless so restricted as to not produce an objectionable variation in the intensity of the light.

The voltage curve of the generator is such that the rise of voltage is most rapid at low 25 speeds and diminishes at higher speeds, due to inductive reactance. To counteract a corresponding rise in current it is necessary to cut in resistance more rapidly at low speeds than at higher speeds. Provision for this 30 effect is made in the construction illustrated in Fig. 2, in which the resistor is in the form of a conical spiral coil M, the convolutions of which are in contact when under the normal pressure of the spring I, but are separated progressively under the action of the 35 spring J, the construction being otherwise the same as in Fig. 1. Thus in operation, after the wire G has been sufficiently expanded to bring the contacts L and K together, the further expansion will permit the 40 spring J to draw upon the conical coil M. This will first separate the larger convolutions from each other, and as the action progresses the smaller ones, with the effect 45 that the resistance is increased by progressively decreasing increments.

What I claim as my invention is:

1. In an electric lighting system for motor vehicles, the combination with a generator 50 varying in voltage with speed changes, of a lamp circuit and a regulator in said lamp circuit comprising a variable resistance resistor, a yieldable tension device for increasing the resistance of said resistor and opposed yieldable tension device greater than and normally overcoming the first-mentioned tension device, a conductor forming a 55 mechanical link between said last-mentioned tension device and the resistor and included in the circuit, said conductor being expandable in proportion to the current passing therethrough, and a stop for limiting the movement of said conductor when expanding 60 in the direction in which it is actuated by said first-mentioned tension device,

whereby the engagement with said stop will permit the lesser tension device to increase the resistance in the circuit upon further expansion of said conductor.

2. In an electric lighting system for motor vehicles, the combination with a generator varying in voltage with speed, of a lamp circuit and a current regulator in said lamp circuit comprising an extensible resistor increasing in resistance as it is extended, a tension device for extending said resistor, an opposed tension device greater than and overcoming said first-mentioned tension device to hold said resistor contracted, a conductor forming a mechanical tie between 75 said last-mentioned tension device and the resistor, being included in the electric circuit and being expansible in proportion to the current passing therethrough, and a stop for limiting movement of said conductor in the direction in which it is actuated by the greater tension device, said stop being spaced to permit an initial expansion of said conductor upon increase in current in the circuit until a predetermined lighting effect 80 is obtained and then limiting movement in this direction to permit the opposed tension device to extend said resistor and increase resistance in the circuit.

3. An electric current regulator comprising a resistor, a yieldable tension device for increasing the resistance of said resistor, an opposed yieldable tension device greater than and normally overcoming the first-mentioned tension device, a conductor forming a mechanical link between the last-mentioned tension device and the resistor included in an electric circuit, said conductor being expansible in proportion to the current passing therethrough, and a stop for limiting the 100 movement of said conductor when expanding in the direction in which it is actuated by said first-mentioned tension device, whereby the engagement with said stop will permit the last-mentioned tension device to 105 increase the resistance in the circuit upon further expansion of said conductor.

4. In an electric system for motor vehicles, the combination with a generator varying in voltage with speed changes, of a lamp circuit and a current regulator for said lamp circuit comprising a compressible resistor and an expandable conductor connected in series in said circuit, said resistor varying in resistance under different degrees of compression, and means acting through said conductor to subject said resistor to a compressive stress to decrease the resistance thereof, said stress being relieved through expansion of said conductor upon a predetermined flow 115 of current therethrough to permit of expansion of said resistor and a consequent increase of the resistance of the same.

In testimony whereof I affix my signature.
JOHN W. FITZ GERALD.
